UNITED STATES PATENT OFFICE.

JOHN C. FRENCH, OF CONCORD, NEW HAMPSHIRE.

CAR-AXLE BOX.

SPECIFICATION forming part of Letters Patent No. 397,637, dated February 12, 1889.

Application filed May 31, 1888. Serial No. 275,566. (No model.)

To all whom it may concern:

Be it known that I, JOHN C. FRENCH, a citizen of the United States, residing at Concord, in the county of Merrimac and State of New Hampshire, have invented certain new and useful Improvements in Car-Axle Boxes, of which the following is a specification.

This invention relates to the rear end of car-axle boxes, the object being to provide better means for the entrance of the "dust-guard," which is formed in two segments, and novel means for retaining the same in proper position.

The invention will be clearly understood by reference to the following specification and claims and the accompanying drawings, forming a part thereof, of which—

Figure 1 is a perspective view of a car-axle box provided with my improvements, Fig. 2 being an end sectional elevation, showing one segment of a dust-guard partly removed. Fig. 3 is a plan of the rear part of the axle-box. Fig. 4 represents a cross-section of the axle-box taken through the dust-guard chamber, 25 showing a modification in construction. Fig. 5 is part end elevation and part cross-section taken through the dust-guard chamber of an axle-box, showing still another modification of my improvements. Fig. 6 shows an end 30 sectional elevation of a car-axle box with other modifications of my improvements. Fig. 7 is a plan of the rear end of an axle-box when constructed as in Fig. 4. Fig. 8 is a plan of the rear end of an axle-box when constructed as in Fig. 5. Fig. 9 represents one side of Fig. 6, showing the cap covering the dust-guard chamber as when closed and firmly secured.

Similar letters indicate corresponding parts throughout the various views.

Heretofore, in one or more instances, a dust-guard made in two segments has been introduced by means of side openings in the dust-guard chamber, the outer portion of either 45 segment of the dust-guard being made to serve the purpose of a cover or cap for the said opening.

In the above construction great difficulty is encountered by reason of the lateral movement of the axle-box upon the axle-journal, which tends to break the fastenings designed 50 to hold the caps or covers over the side open-

ings in said dust-guard chamber, and thus loose a segment of said dust-guard as well as admit dust to said chamber. To avoid these difficulties I provide openings for the entrance of the dust-guard segments in or as near the top of the dust-guard chamber as possible and provide springs for insuring perfect contact of the dust-guard segments with the journal. 60

In the drawings I show various forms of springs, some secured to the dust-guards themselves and others to the caps closing the openings in the dust-guard chamber, either construction serving the same purpose. 65

The dust-guard segments A A may enter the dust-guard chamber b of the axle-box B by means of openings b' b', formed in its top, as seen in Figs. 2, 3, 5, and 8, or by means of a single long opening, b², as in Figs. 4 and 7; or openings may be formed in each upper corner of the dust-guard chamber, partly in its sides and partly in its top, as at b³ b³, Figs. 6 and 9.

Springs C C may be secured to each segment of the dust-guard crossing each other, as in Fig. 2, and bearing against the walls of the dust-guard chamber b on each side of the axle-box; or, in case a single opening, b², is used for the entrance of the dust-guard segments, a 80 yoke-spring, C' C', may be fastened to the cap or cover D', which is conveniently fastened by screws d d to the axle-box. Similar springs, C² C³, may also be secured, respectively, to the caps D² D³, as shown in Figs. 5 and 6. 85 Those shown in Fig. 5 must necessarily be hinged, as at c c, however, in order to allow the cap to be raised.

The caps or covers for the openings in the dust-guard chamber may be variously secured, 90 screws d d serving the purpose in some cases; but when the said caps extend over the sides, as is seen in Figs. 1, 2, 3, 6, and 9, other means may be preferable—such as the round-headed stud F, secured to the cap, and held by a 95 spring-hook, G, attached to the axle-box, (seen in Figs. 1, 2, and 3;) or a stud, H, may project from the axle-box, and, passing through a slot, d', in the cap or cover D², receive and support a slotted retaining-piece, I, between its outer bent end, h, and the said cap D³. The piece I should be tapered slightly from top to bottom and connected by a spring, i, to the axle-box, so as to hold the cap tightly to said 100

axle-box, as seen in Fig. 6. One of the caps, D', is shown to have a tongue, d², filling the opening b' in the dust-guard chamber, and the spring C² is hinged to said tongue portion.

5 The dust-guard segments A A may have a slot, a, at any convenient point for hooking onto for the purpose of removal from the dust-guard chamber.

To prevent the dust-guard segments from 10 turning in the dust-guard chamber, I show in Fig. 5 a portion of the metal from which the springs C² are formed projecting downward from the hinge or pivotal point c, as at c' c', against which the upper part of said dust-guard may strike. Any equivalent for the parts c' may be used, however—*i. e.*, a stop-lug may extend downward from either of the caps D', D², or D³.

An important feature of my invention is 20 the enlargement of the dust-guard chamber b in a direction crosswise of the axle-box sufficiently to admit of the passage of a dust-guard segment on either side of the journal-bearing E in a vertical direction, as clearly 25 shown in the drawings.

A threaded opening, to which is fitted a screw or plug, J, is made in one or both sides of the dust-guard chamber b, for the purpose of conveniently cleaning the said chamber.

30 Having described my invention, what I claim

as new, and desire to secure by Letters Patent, is—

1. The combination, with a car-axle box having a dust-guard chamber, of hollow side flanges forming extensions for said chamber, 35 covered openings formed partly in said extensions or flanges at each side of the journal-bearing, and a dust-guard formed in two segments, each adapted to enter either of said covered openings, having slots to facilitate 40 their removal and springs for maintaining continuous contact with the journal.

2. The combination of a dust-guard formed in two segments, and a chamber in the car-axle box extending beyond the side walls of 45 said box into flanges formed for this purpose on its sides, having openings in its top for admitting either segment of said dust-guard on opposite sides of the journal, and one or more threaded openings at its bottom closed by 50 screw-plugs, and covers for said top openings provided with suitable fastenings and springs for maintaining continuous contact of the dust-guard segments with the journal.

In testimony whereof I affix my signature in 55 presence of two witnesses.

JOHN C. FRENCH.
